(57) **CLAIM**

The ornamental design for a display screen with animated graphical user interface, as shown and described.

DESCRIPTION

FIG. 1 is a front view of an electronic device with display screen with animated graphical user interface showing a first image in a sequence according to the claimed design; FIG. 2 is a front view thereof showing a second image in the sequence;

FIG. 3 is a front view thereof showing a third image in the sequence; and,

FIG. 4 is a front view thereof showing a fourth image in the sequence.

The appearance of the transitional image sequentially transitions between the images shown in FIGS. 1-4.

The process or period in which one image transitions to another image forms no part of the claimed design. The sharp-cornered broken-line rectangle shows the perimeter of a display screen. The broken lines outside this perimeter show portions of an electronic device. The broken lines within the perimeter show features of a graphical user interface. The broken lines form no part of the claimed design.

1 Claim, 4 Drawing Sheets
